ROLLER SKATE WHEEL

Frank J. Wagner, Franklin Square, N. Y., assignor
or of one-half to Carroll M. Bierman, Franklin
Square, N. Y.

Application April 19, 1946, Serial No. 663,504

8 Claims. (Cl. 301—5.7)

1

This invention relates to roller skate wheels in general, and more especially to the roller skate wheels used in the skates of professional skaters, performers, and the like.

Among the objects of the present invention, it is aimed to provide an improved roller skate wheel having a bearing and ornamental disk intimately associated with one another.

It is still another object of the present invention to provide an improved roller skate wheel having a tread member, a one piece bearing housing, a ball bearing assembly in said shell, a provision for expeditiously locking the several units to one another, and in addition interchangeably connected ornamental disks.

These and other features, capabilities and advantages of the invention will appear from the subjoined detail description of one specific embodiment thereof illustrated in the accompanying drawings, in which

Fig. 1 is a side elevation of a roller skate wheel made according to the present invention.

Fig. 2 is a transverse section of the wheel.

In the embodiment shown, the wheel 1 includes a tread member 2 preferably composed of wood such as maple and the like, the tread in the present instance having an axial opening 3 in communication with the opening 4, both openings terminating in annular recesses, the opening 3 in the annular recess 5, and the opening 4 in the annular recess 6. While the dimensions may vary without departing from the general spirit of the invention, excellent results have been achieved when the openings 3 and 4 are co-axial, the opening 3 having not only a smaller diameter than the opening 4, but also being narrower in depth. As an instance, with the diameter for the tread 2 of approximately 4½ inches, the diameter of the opening 3 should not exceed 1½ inches as compared to 2 inches for the diameter of the opening 4, and the width of the opening 3 should not exceed 5/16 of an inch as compared to 13/16 inches for the width of the opening 4. In the present instance, the recesses 5 and 6 also differ relative to one another, the recess 5 having an outer diameter of substantially 23/4 inches while the recess 6 has an outer diameter of substantially 3 inches, while the width of the recess 5 does not exceed 5/16 of an inch as compared to 3/16 of an inch for the width of the recess 6.

Having a substantial machine fit with the openings 3 and 4, there is provided the bearing housing or shell 1, having a main tubular portion 8 disposed in the opening 4, and a diminished tubular portion 9 disposed in the opening 3 with the

2

intermediate shoulder 10 of the shell 1 engaging the intermediate shoulder 11 of the tread 2 between the openings 3 and 4.

The shell 1, as shown, preferably has an annular extension 12 formed intermediate the openings 3 and 4.

For anchoring the shell 1 in the tread 2, there is provided the annular disk 13 having threads on its inner periphery engaging the threads on the outer periphery of the free end of the tubular portion 9. The disk 13, preferably is provided with spanner recesses 14 and 15 to receive a spanner and turn the disk 13 into position in the recess 5.

15 In the tubular portion 8, there are housed the two ball bearing units 16 and 17 which have the outer collars 18 and 19, respectively, and the inner collars 20 and 21, respectively. The collars 18 and 20 support between them the set of ball bearings 16 and 17 and the collars 19 and 21 support between them the set of ball bearings 23. The outer periphery of the collars 18 and 19 is finished to have a machine fit with the inner periphery of the tubular portion 8. The ball bearing unit 17, in the present instance, is disposed against the annular extension 12 and the inner collars 20 and 21 are preferably spaced from one another by the spacer 24. After the ball bearing units 16 and 17 are so positioned with the spacer 24 in the tubular portion 8, then the same may be anchored in position by the collar 25 screw threadedly connected to the internal screw threads on the outer end of the tubular portion 8. This collar 25, as shown, is provided with spanner recesses 26 and 27 to receive a spanner and turn the collar 25 into position for locking the bearings 16 and 17 in place.

In the present instance, the collar 25 also has an internal screw thread to receive the external screw thread of the cap 28. This cap 28, in the present instance, has a tubular portion 29 and a head 30 terminating in a polygonal shape hexagonal in the present instance to receive a wrench. Preferably the wrench receiving polygonal portion is wide enough to receive a wrench, excellent results having been achieved when this rise 31 does not exceed 5/16 of an inch.

The polygonal edge portion of the head 30, furthermore, extends beyond the outer periphery of the tubular portion 29, so that, as shown, there 50 may be anchored between the shoulder 31 and the inner face of the recess 6 and also the outer ends of the tubular portion 8 and collar 25, one or more ornamental disks, two of such disks being shown in the present instance, to wit, the disks 32 and 33, the disk 33 having an outer diameter

substantially coincident with the outer periphery of the recess 6, while the outer diameter of the disk 32 is smaller in the interest of a predetermined ornamental effect, and the inner diameters of both disks 32 and 33 preferably coincide with the outer periphery of the tubular portion 29 of the cap 28. Various combinations of colors may be selected for the outer face of the cap 28, and the outer faces of the disks 32 and 33, to create the ornamental effect to be produced. In some instances, the silver sheen of a chromium finish on the outer face of the head 30 of the cap 28 may form part of a color scheme where the outer face of the disk 32 is red in color, and the outer face of the disk 33 is green in color.

Before the cap 28 is screwed into position in assembly of the roller skate wheel to the truck of a wheel, preferably the axle 34 of the truck has its diminished portion 35 positioned in the inner collars 20 and 21 of the ball bearing units 16 and 17, respectively, and then the washer 36 and nut 37 secured in place.

While the tread 2 is preferably composed of wood, such as maple wood, the shell 7, annular disk 13, bearing units 16 and 17, collar 25 and cap 28 are preferably composed of metal such as steel or the like, the ornamental disks 32 and 33 may be composed either of a suitable metal with an enamel colored coating or composed of a colored light transmitting plastic material. The free end of the tubular portion 8 may terminate flush with the inner face of the recess 6, but the free end of the tubular portion 9 preferably extends beyond the inner face of the recess 5 to receive annular locking disk 23.

It is obvious that various changes and modifications may be made to the details of construction without departing from the general spirit of the invention as set forth in the appended claims.

I claim:

1. In a roller skate wheel, the combination of a tread having a central chamber including an enlarged cylindrical chamber, a diminished cylindrical chamber, an annular shoulder defining the enlarged from the diminished chamber, and an annular recess at the end of each chamber formed in the lateral faces of said tread, a shell having an enlarged tubular portion conforming to and fitting in said enlarged chamber and a diminished tubular portion conforming to and fitting in said diminished chamber, an inwardly extending annular extension defining said tubular portions from one another, with the enlarged tubular portion terminating at the outer end of the enlarged chamber and the diminished tubular portion terminating beyond the outer end of the diminished chamber, an annular disk screw threadedly connected to the free end of the diminished tubular portion and disposed in one of said recesses to anchor said shell in place, an axle receiving bearing assembly disposed against said annular extension in said enlarged tubular portion, an annular collar screw threadedly connected in the free end of said enlarged tubular portion and anchoring said bearing assembly in place, a cap having a head screw threadedly connected to the inner periphery of said annular collar, and ornamental means secured between said head and the inner face of said other recess to anchor said ornamental means in position.

2. In a roller skate wheel, the combination of a tread having a central chamber including an enlarged cylindrical chamber, a diminished cylindrical chamber, an annular shoulder defining the enlarged from the diminished chamber, and an

annular recess at the end of each chamber formed in the lateral faces of said tread, a shell having an enlarged tubular portion conforming to and fitting in said enlarged chamber and a diminished tubular portion conforming to and fitting in said diminished chamber, an inwardly extending annular extension defining said tubular portions from one another, with the enlarged tubular portion terminating at the outer end of

10 the enlarged chamber and the diminished tubular portion terminating beyond the outer end of the diminished chamber, an annular disk screw threadedly connected to the free end of the diminished tubular portion and disposed in one of said recesses to anchor said shell in place, an axle receiving bearing assembly disposed against said annular extension in said enlarged tubular portion, an annular collar screw threadedly connected in the free end of said enlarged tubular

20 portion and anchoring said bearing assembly in place, a cap having a head screw threadedly connected to the inner periphery of said annular collar, and ornamental means including a disk secured between said head and the inner face of 25 said other recess to anchor said ornamental means in place.

3. In a roller skate wheel, the combination of a tread having a central chamber including an enlarged cylindrical chamber, a diminished cylindrical chamber, an annular shoulder defining the enlarged from the diminished chamber, and an annular recess at the end of each chamber formed in the lateral faces of said tread, a shell having an enlarged tubular portion conforming to and fitting in said enlarged chamber and a diminished tubular portion conforming to and fitting in said diminished chamber, an inwardly extending annular extension defining said tubular portions from one another, with the enlarged

35 tubular portion terminating at the outer end of the enlarged chamber and the diminished tubular portion terminating beyond the outer end of the diminished chamber, an annular disk screw threadedly connected to the free end of the diminished tubular portion and disposed in one of

40 said recesses to anchor said shell in place, an axle receiving bearing assembly disposed against said annular extension in said enlarged tubular portion, an annular collar screw threadedly connected in the free end of said enlarged tubular portion and anchoring said bearing assembly in place, a cap having a head screw threadedly connected to the inner periphery of said annular collar, and two ornamental disks of different diameters, with the larger disk disposed against the inner face of said other recess and the smaller disk disposed between said head and said larger disk.

4. In a roller skate wheel, the combination of a tread having a central chamber including an enlarged cylindrical chamber, a diminished cylindrical chamber, an annular shoulder defining the enlarged from the diminished chamber, and an annular recess at the end of each chamber formed

55 in the lateral faces of said tread, a shell having an enlarged tubular portion conforming to and fitting in said enlarged chamber and a diminished tubular portion conforming to and fitting in said diminished chamber, an inwardly extending annular extension defining said tubular portions from one another, with the enlarged tubular portion terminating at the outer end of the enlarged chamber and the diminished tubular portion terminating beyond the outer end of the diminished chamber, an annular disk screw threadedly con-

nected to the free end of the diminished tubular portion and disposed in one of said recesses to anchor said shell in place, an axle receiving bearing assembly disposed against said annular extension in said enlarged tubular portion, and means including a cap screw threadedly connected to the inner periphery of the outer end of said enlarged tubular portion to anchor said bearing assembly in place.

5. In a roller skate wheel, the combination of 10 a tread having a central chamber including an enlarged cylindrical chamber, a diminished cylindrical chamber, an annular shoulder defining the enlarged from the diminished chamber, and an annular recess at the end of each chamber formed in the lateral faces of said tread, a shell having an enlarged tubular portion conforming to and fitting in said enlarged chamber and a diminished tubular portion conforming to and fitting in said diminished chamber, an inwardly extending annular extension defining said tubular portions from one another, with the enlarged tubular portion terminating at the outer end of the enlarged chamber and the diminished tubular portion terminating beyond the outer end of the diminished chamber, an annular disk screw threadedly connected to the inner periphery of the outer end of said enlarged tubular portion to anchor said bearing assembly in place.

6. In a roller skate wheel, the combination of a tread having a central chamber including an enlarged cylindrical chamber, a diminished cylindrical chamber, an annular shoulder defining the enlarged from the diminished chamber, a shell having an enlarged tubular portion conforming to and fitting in said enlarged chamber and a diminished tubular portion conforming to and fitting in said diminished chamber, an inwardly extending annular extension defining said tubular portions from one another, with the enlarged tubular portion terminating at the outer end of the enlarged chamber and the diminished tubular portion terminating beyond the outer end of the diminished chamber, an annular disk screw threadedly connected to the free end of the diminished tubular portion to anchor said shell in place, an axle receiving bearing assembly disposed against said annular extension in said enlarged tubular portion, an annular collar screw threadedly connected in the free end of said enlarged tubular portion and anchoring said bearing assembly in place, a cap having a head screw

threadedly connected to the inner periphery of said annular collar, and ornamental means secured between said head and the inner face of said other recess to anchor said ornamental means in position.

7. In a roller skate wheel, the combination of a tread having a central chamber including an enlarged cylindrical chamber, a diminished cylindrical chamber, an annular shoulder defining the enlarged from the diminished chamber, a shell having an enlarged tubular portion conforming to and fitting in said enlarged chamber and a diminished tubular portion conforming to and fitting in said diminished chamber, an inwardly extending annular extension defining said tubular portions from one another, with the enlarged tubular portion terminating at the outer end of the enlarged chamber and the diminished tubular portion terminating beyond the outer end of the diminished chamber, an annular disk screw threadedly connected to the free end of the diminished tubular portion to anchor said shell in place, an axle receiving bearing assembly including two ball bearing units and a spacer between the two in said enlarged tubular portion, an annular collar screw threadedly connected in the free end of said enlarged tubular portion and anchoring said bearing assembly in place, a cap having a head screw threadedly connected to the inner periphery of said annular collar, and ornamental means secured between said head and the inner face of said other recess to anchor said ornamental means in position.

8. In a roller skate wheel, the combination of 35 a tread having a central chamber including an enlarged cylindrical chamber, a diminished cylindrical chamber, an annular shoulder defining the enlarged from the diminished chamber, a shell having an enlarged tubular portion conforming to and fitting in said enlarged chamber and a diminished tubular portion conforming to and fitting in said diminished chamber, an inwardly extending annular extension defining said tubular portions from one another, with the enlarged 40 tubular portion terminating at the outer end of the enlarged chamber and the diminished tubular portion terminating beyond the outer end of the diminished chamber, an annular disk screw threadedly connected to the free end of the diminished tubular portion to anchor said shell in place, an axle receiving bearing assembly including two ball bearing units and a spacer between the two in said enlarged portion, and means 45 including a cap screw threadedly connected to the inner periphery of the outer end of said enlarged tubular portion to anchor said bearing assembly in place.

FRANK J. WAGNER.
